CLAIM

The ornamental design for a sofa set as shown and described.

DESCRIPTION

FIG. 1 is a front, right and top perspective view of the single sofa of the sofa set in FIG. 1.

FIG. 2 is a rear, left and bottom perspective view of the single sofa of the sofa set in FIG. 1.

FIG. 3 is a front elevation view of the single sofa of FIG. 1.

FIG. 4 is a rear elevation view of the single sofa of FIG. 1.

FIG. 5 is a left side elevation view of the single sofa of FIG. 1.

FIG. 6 is a right side elevation view of the single sofa of FIG. 1.

FIG. 7 is a top plan view of the single sofa of FIG. 1.

FIG. 8 is a bottom plan view of the single sofa of FIG. 1.

FIG. 9 is a front, right and top perspective view of the double seat sofa of the sofa set in FIG. 9.

FIG. 10 is a rear, left and bottom perspective view of the double seat sofa of the sofa set in FIG. 9.

FIG. 11 is a front elevation view of the double seat sofa of FIG. 9.

(Continued)

FIG. 12 is a rear elevation view of the double seat sofa of FIG. 9.

FIG. 13 is a left side elevation view of the double seat sofa of FIG. 9.

FIG. 14 is a right side elevation view of the double seat sofa of FIG. 9.

FIG. 15 is a top plan view of the double seat sofa of FIG. 9.

FIG. 16 is a bottom plan view of the double seat sofa of FIG. 9.

FIG. 17 is a front, right and top perspective view of the three seats sofa of the sofa set in FIG. 17.

FIG. 18 is a rear, left and bottom perspective view of the three seats sofa of the sofa set in FIG. 17.

FIG. 19 is a front elevation view of the three seats sofa of FIG. 17.

FIG. 20 is a rear elevation view of the three seats sofa of FIG. 17.

FIG. 21 is a left side elevation view of the three seats sofa of FIG. 17.

FIG. 22 is a right side elevation view of the three seats sofa of FIG. 17.

FIG. 23 is a top plan view of the three seats sofa of FIG. 17.

FIG. 24 is a bottom plan view of the three seats sofa of FIG. 17.

FIG. 25 is an enlarged view of detail 25 in FIG. 18.

FIG. 26 is a front, right and top perspective view of the Sectional sofa of the sofa set in FIG. 26.

FIG. 27 is a rear, left and bottom perspective view of the Sectional sofa of the sofa set in FIG. 26.

FIG. 28 is a front elevation view of the Sectional sofa of FIG. 26.

FIG. 29 is a rear elevation view of the Sectional sofa of FIG. 26.

FIG. 30 is a left side elevation view of the Sectional sofa of FIG. 26.

FIG. 31 is a right side elevation view of the Sectional sofa of FIG. 26.

FIG. 32 is a top plan view of the Sectional sofa of FIG. 26.

FIG. 33 is a bottom plan view of the Sectional sofa of FIG. 26.

FIG. 34 is an enlarged view of detail 34 in FIG. 27; and,

FIG. 35 is a front, right and top perspective view of a sofa set showing my design.

The dot-dash broken lines in FIGS. 18, 25, 27 and 34 depict the boundaries of the enlargements that form no part of the claimed design.

1 Claim, 35 Drawing Sheets
